Patented Nov. 20, 1917.

UNITED STATES PATENT OFFICE.

CLARKSON E. PICKARD AND EDWARD L. CONDON, OF MARSHALLTOWN, IOWA.

COMBINED BALANCE AND LEVELING HINGE FOR PIANO-KEYS.

1,246,997.

Specification of Letters Patent.

Patented Nov. 20, 1917.

Application filed April 25, 1916. Serial No. 93,562.

To all whom it may concern:

Be it known that we, CLARKSON E. PICKARD and EDWARD L. CONDON, citizens of the United States, residing at Marshalltown, in the county of Marshall and State of Iowa, have invented certain new and useful Improvements in Combined Balance and Leveling Hinges for Piano-Keys, of which the following is a specification.

10 This invention relates to an improved piano key mounting and more particularly to a combined balancing and leveling hinge for the key.

15 The invention has as its primary object to provide a construction which will eliminate the use of the ordinary balance pin and which will accordingly also eliminate the necessity for the presence of an opening in the key to receive the said pin.

20 The invention has as a further object to provide a device of this character wherein the key may be adjusted relative to the body of the hinge for leveling the key.

25 And a still further object of the invention is to provide a hinge having a felt or other fibrous bushing so associated therewith that the said hinge will be entirely silent in operation.

Other and incidental objects will appear 30 as the description proceeds and in the drawings wherein we have illustrated the preferred embodiment of the invention and wherein similar reference characters designate corresponding parts throughout the several views,

35 Figure 1 is a side elevation showing a piano key equipped with one of our improved hinges, the key being shown in connection with a conventional type of key bed which is illustrated partly in section,

40 Fig. 2 is a sectional view more particularly showing the construction and mounting of the hinge,

45 Fig. 3 is a detail perspective view of the body of the hinge detached,

Fig. 4 is a plan view showing the blank from which the body of the hinge is formed.

50 In order that the construction, mounting and operation of our improved hinge may be more readily understood, we have, in the

drawings, shown the improved device in connection with a usual type of piano key 10 with which is associated a key frame 11 having a front rail 12, a center rail 13 and a back rail 14 upon the upper side of which 55 is arranged the usual felt 15 to come beneath the rear end of the key.

In carrying out the invention, we employ a hinge body of the type illustrated in detail in Fig. 3 of the drawings. This hinge body 60 is preferably formed of resilient sheet metal, although any other suitable material may be employed and includes a flat bottom wall 16 which is provided at opposite sides thereof, with coacting upstanding flanges 17. The hinge body is preferably formed from a blank as illustrated in detail in Fig. 4 of the drawings. This blank is substantially circular and is formed with spaced parallel fold lines at opposite sides of the center thereof to define the said bottom wall 16 as well as the flanges 17. Struck from the bottom wall 16, at a point substantially midway the ends thereof are coacting pintle lugs or ears 18 which are bent to depend from the bottom 75 wall 16 at opposite sides thereof and are formed with suitable registering openings. It will be noted that in thus striking the lugs 18 from the bottom wall 16, an opening 80 is provided in the said bottom wall. The purpose of this opening will presently appear.

The hinge body as thus formed receives the key 10 between the flanges 17 thereof with the said flanges confronting opposite 85 sides of the key and with the key seated against the bottom wall 16 of the hinge body. Connecting the hinge body to the key, are front and rear screws or other suitable fastening devices 19 and 19' respectively. The front screw 19 is engaged in a suitable notch in the bottom wall 16 of the hinge body at one extremity thereof while the rear screw 19' is freely fitted through a suitable opening formed in the said bottom 95 wall adjacent the opposite extremity of the hinge body, these screws being threaded into the bottom of the key. Preferably, the key 10 is, as best shown in Fig. 2 of the drawings, cut away to receive the hinge body so 100

them on to the exposed or fixed contact surface between the openings of which fixed contact surface the printing light penetrates.

5 The sensitized paper 2 and drawing 3 are carried by the moving contact surface 4 in close contact with the fixed surface 6 and are eventually guided out from between the fixed and moving contact surfaces on to the table 15 as indicated at 16 and 17, there 10 being a guide or shield 18, similar to the aforesaid guide 5, and which is mounted on the rod 55, facilitating the discharge of the drawing and sensitized paper on to the table 15.

15 The fixed contact surface having its body formed of fine screen or mesh material has properties and advantages over glass. It may be made more transparent than glass. It will not crack or break because of heat.

20 One of the most important features of this particular character of contact surface is that tracings will not slip as they frequently do on glass surfaces. This slipping is caused apparently by the electrification of 25 the glass.

What is claimed is:—

1. A blue print machine comprising a fixed member composed of fine wire mesh and affording a curved contact surface and 30 a moving member having a contact surface for carrying the work through the machine in engagement with the fixed curved contact surface, the wires of the mesh being inclined to the direction of the movement of 35 the material through the machine.

2. A blue print machine comprising a fixed member composed of fine wire mesh and affording a curved contact surface and a moving member having a contact surface 40 for carrying the work through the machine in engagement with the fixed contact surface and in a direction substantially at right angles to the longitudinal axis of the fixed contact surface, the fine wires of the wire 45 mesh being inclined to the direction of movement of the material through the machine.

3. A blue print machine comprising a fixed member composed of fine wire mesh 50 and affording a curved contact surface, a moving member having a contact surface for carrying the work through the machine in engagement with the fixed contact surface and in a direction substantially at right

angles to the longitudinal axis of the fixed 55 contact surface, the fine wires of the wire mesh being inclined to the direction of movement of the material through the machine, and a metal frame work composed of wire mesh stretched tightly over the aforesaid wire mesh and whose wires are inclined to the direction of movement of the material through the machine. 60

4. A blue print machine comprising a fixed contact member which is provided with a longitudinal opening in its top and which is provided with a curved contact member composed of fine wire mesh material, a moving contact member for carrying the work through the machine in engagement with the surface of the fixed member and in a direction substantially at right angles to the longitudinal axis of the fixed contact surface, the fine wires of the wire mesh being inclined to the direction of movement of the material through the machine, a lamp support, and a lamp suspended from said support to throw rays of light into said fixed member through said opening in the top thereof. 65

5. A blue print machine comprising a fixed member composed of fine wire mesh affording a contact surface, a moving member having a contact surface to carry the work through the machine in engagement 85 with the fixed contact surface, the fine wires of the fixed member being inclined to the direction of movement of the material through the machine, and a strengthening member for said fine wire mesh fixed contact member composed of wires inclined to the line of movement of the material through the machine. 90

6. A blue print machine comprising a fixed member composed of fine wire mesh 95 and affording a contact surface, and a moving member having a contact surface for carrying the work through the machine in engagement with said fixed member, the wires of the mesh being inclined to the direction of the movement of the material through the machine. 100

In testimony whereof I affix my signature in presence of two witnesses.

JOSEPH L. MARQUIS.

Witnesses:

LEON J. MARQUIS,
VICTOR HABER.

by the hinge body at one side thereof and arranged opposite said opening, a flange engaged at one extremity with said pintle and supporting the hinge body to rock 5 upon the flange, and means disposed in said opening and bearing against the adjacent extremity of the flange for cushion-

ing the hinge body upon the flange under the load of a key.

In testimony whereof we affix our signatures.

CLARKSON E. PICKARD. [L.S.]
EDWARD L. CONDON. [L.S.]
